US00D571198S

(12) **United States Design Patent** (10) **Patent No.:** **US D571,198 S**
Lee et al. (45) **Date of Patent:** **** Jun. 17, 2008**

(54) **WIRELESS OPTICAL MOUSE PACKAGING BOX**

(75) Inventors: **Pe-Su Lee**, Taoyuan County (TW);
Shuo-Hsiu Chang, Taipei County (TW); **Ya-Fang Yang**, Taoyuan County (TW)

(73) Assignee: **Darfon Electronics Corp.**, Taoyuan (TW)

(**) Term: **14 Years**

(21) Appl. No.: **29/276,276**

(22) Filed: **Jan. 19, 2007**

(30) **Foreign Application Priority Data**

Jul. 20, 2006 (TW) 95304070

(51) **LOC (8) Cl.** **09-03**

(52) **U.S. Cl.** **D9/432**

(58) **Field of Classification Search** D9/430–433, D9/414–418, 420–429, 560, 737, 756; D3/273, D3/302; 206/421, 454, 457, 775–778, 784, 206/822; 220/500, 523–529, 552, 555; 229/100, 103.3, 104–106, 108, 108.1, 109, 229/110, 112–116, 116.1, 116.2, 117.15, 229/120, 125.015, 132, 138, 155, 162.1, 229/162.6, 162.7, 182.1, 213, 214, 247, 406, 229/407, 902, 911, 922, 930, 942

(57) **CLAIM**

The ornamental design for a wireless optical mouse packaging box, as shown and described.

DESCRIPTION

FIG. 1 is a perspective view thereof;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
